DOOR SERVICE GUARD

Leo Peters, Evanston, Ill.

Application April 23, 1949, Serial No. 89,265

6 Claims. (Cl. 20—16)

1

This invention relates to a door service guard, and is particularly useful in the safeguarding of garments which are to be picked up for dry cleaning, etc. and returned by the deliveryman.

The problem of providing adequate and satisfactory means for eliminating inconveniences now present in the pick-up and delivery of dry cleaning runs into many practical difficulties. For example, doors to which a servicing structure might be attached vary considerably in their structure. Some doors are of metal, others of wood, and still others of a combination of the two materials. Some doors are of solid construction; others have panels of various kinds and thickness; still others have large or small panes of glass for decoration or to admit light. Some doors have wide frames while others have narrow frames. Doors which are made of hard wood or metal are difficult to cut, drill, chisel or rabbet. Some home owners seriously object to having holes drilled or grooves rabbeted in their doors, while all of them prefer to have door alterations held to a minimum when a door service case or guard is installed. Some home owners also object to having a door case attached that partially or wholly covers any door windows that might be present.

An object of the present invention is to overcome, or reduce to a minimum, the above difficulties and objections. A further object is to provide simple and effective means for safeguarding garments upon a building panel or door when the same is to be picked up or after the garments are delivered during that interval of time during which the housewife is not at home. A further object is to provide a guard panel which can be folded, rolled, telescoped, or meshed outward or inward at will to cover and uncover clothes hanging on the outside of a door or wall. A further object is to provide a lock, controlled by a combination, key, etc., and an extensible gate fastened to the outside of a door for automatically unlocking when the door is opened and automatically locking when the door is closed, the lock being adapted to be opened by an authorized person when the door is closed. A further object is to provide a locking arrangement for an extensible clothes guard which will use the door frame for locking the guard in position when the door is closed. Yet another object is to provide an extensible clothes guard of open lattice-like construction so as to admit light therethrough to the door windows, while providing a protection for the windows and while, when not in use, may be retracted to a

2

position to one side of the windows. A still further object is to provide a flexible clothes guard which presses against the clothes and holds them tightly in position regardless of how few or many

5 clothes are held within it, the guard being extendible or contractible to any desired extent depending upon the quantity of the clothes which must be secured. A further object is to provide a clothes guard which is not dependent upon any 10 spring action or movable parts to lock it or unlock it as the door is opened and closed and which may be held in closed position due simply to the juxtaposition of stationary frame parts. A still further object is to provide a clothes guard 15 which does not require that the door be mutilated by holes, grooves, etc., while at the same time providing a sturdy safeguard for the clothes when suspended upon the rear door or other door or wall. Other specific objects and advantages 20 will appear as the specification proceeds.

The invention is illustrated, in a specific embodiment, by the accompanying drawing, in which—

25 Figure 1 is a perspective view of a door equipped with garment-retainer structure embodying my invention; Fig. 2, a view similar to Fig. 1 but showing the gate in extended position; Fig. 3, a transverse sectional view, the section being taken as indicated at line 3 of Fig. 2; Fig. 4, an enlarged detailed sectional view showing the lock mechanism in not engaged position; Fig. 5, a view similar to Fig. 4 but showing the lock mechanism engaging the extensible gate; Fig. 6, a broken perspective view of the gate 30 structure which may be employed; and Fig. 7, a perspective view of the lock mechanism, including a latch member forming a part of the locking mechanism.

In the illustration given, A designates a door 40 which is mounted within a door frame B, and C designates an extensible gate.

While the garment-retainer structure may be mounted upon any building panel or wall, I prefer to mount it upon a door A, as illustrated in the drawings. I equip the door with a hook 10. Preferably, on the upper portion of the door and below the hook 10 and to each side thereof are guard posts 11. A garment hanger 12 may be suspended upon the hook 10 to carry garments 45 which may be enclosed within a bag 13. The guard posts 11 may be omitted and the loop portion of the hanger 12 below the hook extended over the hook 10 of the door. The loop of the hanger will thus prevent upper movement 50 of the hanger 12. The frame B may be of the

usual frame which surrounds a door. The gate C may be of any suitable construction and may consist of any body which may be swung into enclosing position about the hook 10 so as to retain the garment thereon. In the specific illustration given, I provide a network of links 14 pivoted together at their points of crossing so as to form an extensible gate. The innermost ends of the links are provided with rollers 15 which are received within a U-shaped track member 16. The track member 16 is connected by a hinge 17 to a base member 18, which is secured to the door. Since this structure is of well-known construction a further detailed description is believed unnecessary. In the specific form of gate C shown, I prefer to equip the outermost link members with flanges 19 in which are formed locking recesses 20.

Any suitable means may be employed for latching or locking the gate C in extended position. For example, a single bolt may be provided for extending over the extended link structure and into juxtaposed relation with the door frame. In the specific illustration given, I equip the door with sleeves 21 which have screws 22 extending into the door. Rotatably mounted in the sleeves 21 is a shaft 23 having end hooks 24 adapted to engage the openings 20 in the gate C. The shaft 23 is also provided with a central hook or latch 25 which is adapted to engage the central portion of the links 14, as shown more clearly in Figs. 2, 3 and 5.

Adjacent the central latch or hook 25 is a lock 26 having a bolt 27 adapted to be moved forwardly into engagement with the latch or hook 25, as shown more clearly in Fig. 5. The lock illustrated is adapted to be actuated by a key, but it will be understood that the lock may, if desired, be a combination lock or may have other means for preventing the operation of the lock by an unauthorized person.

Operation

In the operation of the apparatus, the housewife may place the garments which are to be dry cleaned upon hangers 12 and suspend them upon the hook 10, the bolt 27 of the lock being in extended position, as shown in Fig. 5. The housewife may then draw the gate C into extended position, as shown in Fig. 2, and while the door is open, may secure the gate upon the latch members 24 and 25. When the door is closed, the door frame prevents the further extension of the gate to permit removal of the garment, as illustrated best in Fig. 3. At this time, the housewife still has access to the garments by opening the door, the gate being then extensible to permit its release from the latches 24 and 25. No one else, however, has access to the garments except the pick-up man who is provided with a key for operating the lock to withdraw the bolt 27. Even though the door is locked, the pick-up man can withdraw the bolt 27, swing the latch members 24 and 25 rearwardly to release the gate C and he can thus remove the garments.

After the garments are dry cleaned, the deliveryman may return them in the bag 13 and place the hangers thereof upon the hook 10. The gate C is then drawn about the hook 10 and the latches 24 and 25 brought into engaged relation with the free end of the gate, as illustrated in Figs. 2 and 3. The deliveryman will then insert his key into the lock 26 and move

the bolt 27 into locking position, as illustrated in Figs. 3 and 5.

Upon her return, the housewife may, by unlocking the door, open the door to move the latch parts away from the door frame. The gate may then be slightly extended and released from the latching members 24 and 25, the gate being then contracted or swung outwardly and the garments removed. The extensible gate may be used with a solid door or may, if desired, be arranged to extend over glass windows in the door. In the extended position, the gate does not obscure light from the windows, while at the same time forming a protection for the windows. The metal links 14 of the gate are repellent and permit a bending of the gate about the clothes, as illustrated in Fig. 3, and the extensible character of the gate enables it to accommodate bodies of varying thicknesses.

While in the foregoing specification I have set forth a specific structure in considerable detail for the purpose of illustrating my invention, it will be understood that such details of structure may be varied widely by those skilled in the art without departing from the spirit of my invention.

I claim:

1. In a garment-retainer structure, a support secured to the outside of a door for supporting garments thereon, a lengthwise extensible gate, means carried by the door for supporting the gate upon one side of the door for movement into and away from enclosing position about said support, a latch rotatably mounted upon said door and equipped with hooks for engaging forward portions of said gate when the same is extended over said support, and a bolt-equipped lock carried by said door adjacent said latch, said bolt being movable into position against said latch when the same engages said door to prevent separation of said latch from said gate, said bolt, upon the unlocking of said lock, being retractable to permit disengagement of said gate from said bolt.

2. In a garment-retainer structure, garment support means secured to a door having a door frame, a lazy tong type gate pivotally mounted at one side of said door and extensible over said support means to a position adjacent the door frame at the opposite side of said door, and a lock-controlled latch member engagable with said gate and extending to a position adjacent said door frame to prevent release of said gate while said door is closed, said gate being extensible further beyond said door frame to free said gate from said latch when said door is opened.

3. A garment-retainer structure equipped with means for attaching it upon a door for enclosure of a hook mounted upon the door, said structure comprising a lengthwise extensible gate hingeably mounted upon said door, said gate being extensible for enclosing said hook and to a position adjacent the door frame at the opposite side of the door, a latch rotatably mounted upon said door adjacent said door frame and equipped with hooks for engaging said gate when the same is extended, a bolt-equipped lock adjacent said door frame, said bolt being extensible to engage said latch to maintain the same in gate-engaging position when said gate is extended to a point adjacent said door frame, said latch, when in engagement with said bolt adjacent said door frame, preventing retraction of the gate except when said bolt is withdrawn and said latch opened.

whereby said gate may be longitudinally moved to free it from said latch.

4. In combination with a door hingedly mounted within a door frame and equipped with a door lock, a hook mounted upon the exterior of the door, a lengthwise extensible gate pivotally mounted along the hinged side of the door for movement to an enclosed position about the hook, a key-controlled lock equipped with an extensible bolt, and a latch moving into interlocking engagement with the gate when the same is brought to a position adjacent the door frame, said latch being maintained in interlocking engagement with said gate when said bolt is extended but being releasable therefrom when said bolt is retracted by extending the gate beyond the latch.

5. In combination with a door frame and a door having its exterior side provided with a garment support, a hinge member mounted along one side of said door, an extensible link-gate carried by said hinge and extensible beyond the opposite edge of said door and movable to a position enclosing said support, a latch member on the door adjacent said door frame and movable to positions engaging said gate when the same is extended and for releasing said gate when said gate is extended beyond said latch, and key-controlled locking means adjacent the side of the door opposite said hinge and equipped with a bolt movable into abutting relation with said latch to maintain the latch in interlocking

engagement with said gate, said latch, upon the withdrawal of said bolt, being separable from said gate by moving said gate beyond said latch.

6. In a garment-retainer structure, means upon a door for supporting garments thereon, said door being hinged upon a door frame, an extensible gate upon said door for movement toward the opposite side of said door adjacent said door frame, said gate enclosing said garment-supporting means when in said extended position, a latch upon said door adjacent said door frame and adapted to engage said gate when the same is extended over said garment-supporting means, and a lock having a bolt adapted to be extended to engage said latch to maintain the same in interlocking relation with said gate, whereby extension of said gate is prevented by said door frame, said latch being movable to permit extension of said gate to free it from said latch when said bolt is retracted.
